United States Patent Office

Des. 192,431
Patented Mar. 20, 1962

192,431

GAMEBOARD

William O. Williams, Jr., 1309 Lindhurst Drive,
Gastonia, N.C.

Filed June 22, 1960, Ser. No. 61,072

Term of patent 7 years

(Cl. D34—5)

Fig. 1

Fig. 2

FIG. 1 is a top plan view of a gameboard embodying my new design; and

FIG. 2 is a perspective view of the gameboard of FIG. 1.

The dominant features of the design of the present invention reside in the portions shown in full lines.

I claim:

The ornamental design for a gameboard, as shown and described.
